UNITED STATES PATENT OFFICE.

MORTON HAVENS, JR., OF ALBANY, NEW YORK.

DESIGN FOR A BRANCH BOX FOR INSULATED ELECTRIC WIRES.

No. 39,761.

Specification for Design.

Patented Jan. 12, 1909.

Application filed February 16, 1906. Serial No. 301,506. Term of patent 7 years.

To all whom it may concern:

Be it known that I, MORTON HAVENS, Jr., a citizen of the United States, residing and having my post-office address at No. 79 Chapel street, in the city of Albany, county of Albany, and State of New York, have invented a new, original, and ornamental Design for a Branch Box for Insulated Electric Wires.

In the accompanying drawing, Figure 1 is a perspective view of a branch box for insulated electric wires, embodying my design, and Fig. 2 is a perspective view of said branch box shown as inverted.

This design for branch boxes comprises an elongated body having an open side provided with a closure, and a nipple project-

ing from the side of the body, opposite the closure, the body and the closure having rounding ends and the side of the body opposite the closure rounding in easy curves into the sides and ends of the body, the outer surfaces of the nipple rounding into the adjoining surfaces of the body, and the closure having a projection alined with the nipple.

What I claim is:—

The ornamental design for a branch box for insulated electric wires, substantially as herein shown and described.

MORTON HAVENS, JR.
